Fred W. Martin

ATTORNEY.

UNITED STATES PATENT OFFICE.

MAX J. MILZ, OF TAFT, CALIFORNIA, ASSIGNOR TO MIDWAY IRON WORKS, INC., OF TAFT, CALIFORNIA, A CORPORATION OF CALIFORNIA.

ADJUSTABLE COUNTERBALANCE FOR BAND WHEELS.

Application filed December 14, 1925. Serial No. 75,291.

My invention relates to well equipment and particularly to a band wheel having a novel form of counterbalance. In well equipment and especially in oil well equipment, a band wheel is secured on a rotatable shaft which carries a walking beam crank. The walking beam crank is connected to a pitman which is attached to the walking beam which operates the pump plunger.

10 It is common practice to counterbalance the weight placed on the walking beam by the pump plunger, so as to minimize the power consumption, by securing a weight either to the walking beam or to the band wheel.

It is an object of this invention to provide a band wheel having a counterbalance device possessing novel features which will be explained hereinafter.

20 The weight placed on the walking beam by the pump plunger varies with the depth of the well, and each well must have a certain weight of counterbalance according to its depth.

25 It is an object of this invention to provide a band wheel having a counterbalance device, the counterweight of which may be adjusted radially of the band wheel so that the effective weight may be adjusted to suit the requirements.

30 The rim of the band wheel is adapted to have engagement with a sand reel whereby the sand reel is rotated. The sand reel has a cable wound thereon which is used during 35 different operations at the well, such as handling the pump rods. When the sand reel is operated, the walking beam is not operated and the counterbalance must ordinarily be removed from the band wheel.

40 It is an object of this invention to provide a band wheel having a counterbalance in which the weight may be moved to the center of the wheel without detaching it from the wheel so that there is no eccentric weight placed thereby on the band wheel.

45 It is a still further object of this invention to provide a wooden band wheel having a counterbalance device secured thereto which is so constructed as to serve as a binder for the band wheel and to prevent the counterweight thereof from doing any damage to the band wheel; and also to prevent the band wheel from being spread apart.

Other objects and advantages of the invention will be made evident hereinafter. 55

Referring to the drawings in which I illustrate a preferred form of my invention, Fig. 1 is a diagrammatic view illustrating the utility of my invention.

Fig. 2 is an enlarged face view showing 60 a band wheel having a counterbalance device secured thereto.

Fig. 3 is a section taken on the line 3—3 of Fig. 2.

Fig. 4 is a fragmentary section taken on 65 the line 4—4 of Fig. 2.

Fig. 5 is a fragmentary section taken on the line 5—5 of Fig. 2.

Referring to Fig. 1, 11 denotes a derrick having a band wheel 12 positioned at one 70 side thereof. The band wheel 12 is secured on a rotatable shaft 13 to which a walking beam crank 14, indicated by dotted lines, is secured. The walking beam crank 14 is secured to a pitman 15 which is attached to 75 the outer end of a walking beam 16. The walking beam 16 is adapted to oscillate on the upper end of a Samson post 17. The rim 18 of the band wheel 12 is adapted to engage and drive a sand reel 20 which is 80 supported adjacent thereto.

Referring to Figs. 2 to 5 inclusive, details of the band wheel of my invention will be explained. The band wheel 12 in the drawing is shown as made from wood and is of 85 any standard design. Extending inside the rim 18 are cross members 22 which form a web or spoke portion of the band wheel. At the center of the band wheel 12 and secured to the cross members 22 are hub plates 90 24 through which the shaft 13 extends. The hub plates 24 are secured on each side of the cross members 22 and are both bolted thereto by bolts 25. Secured to the cross members 22 on the front face thereof and at opposite 95 sides of one of the hub plates 24 are inner brackets 27. The inner brackets 27 have feet 28 through which bolts 29 extend for securing them to the cross members 22. Extending between the feet 28 is a cross bar 30 100 and extending outward from the cross bar 30 are legs 32. To the outer ends of the legs 32 rails 33 are secured by bolts 34.

Outer brackets 37 are secured to the rim 18 by bolts 38 and the rails 33 are secured 105 to the outer brackets 37 by bolts 40. As

shown clearly in Fig. 2, the rails 33 extend entirely across the front face of the band wheel and are spaced parallel to each other. Also the rails are placed symmetrically on each side of the shaft 13 of the band wheel 12.

Carried by the rails 33 is a counterweight 42. This counterweight 42 has longitudinal grooves 43 formed in the sides thereof which are adapted to receive the inner edges of the rails 33 as illustrated in Fig. 4. The counterweight 42 is clamped on the rails 33 in a desired radial position by means of clamp plates 45. These clamp plates 45 rest in pockets 46 which are formed adjacent to the grooves 43 so that the outer edges of the clamp plates 45 extend so that they may engage the rails 33. The clamp plates 45 are clamped against the rails 33 by the clamp bolts 46^a which extend through the counterweight 42 and through the clamp plates 45. As shown in Fig. 2, the counterweight 42 is provided with a central slot 48. This slot 48 is provided so that the counterweight 42 may be moved into concentricity with respect to the shaft 13 of the band wheel 12. As shown by dotted lines 49 of Fig. 2, when the counterweight 42 is moved into innermost position the shaft 13 extends through the central slot 48. The counterweight 42 may be clamped in any radial position between that shown by dotted lines 49 in Fig. 2 and between that shown by full lines in Fig. 2.

As previously mentioned, during the pumping of a well it is desirable as a means of reducing power consumption to counterbalance the weight placed on the walking beam by the pump plunger. In my invention the weight of the plunger on the walking beam 16 is counterbalanced by the counterweight 42. By reason of the radial adjustability of the counterweight 42, this weight may be moved into the proper position to obtain the proper effective weight to counterbalance the weight of the plunger on the walking beam 16. It is quite obvious that as the counterweight 42 is moved away from the center of the band wheel 12, the effective weight thereof is increased. Because of the adjustability of the counterweight 42 a standard band wheel of my invention may be a part of every well equipment, it being necessary only to adjust the position of the counterweight 42 when pumping is commenced.

When the pump or the pump rods are to be pulled, the walking beam 15 is disconnected from the band wheel 12 and the sand reel 20 is employed to handle the pump rods. At this time no counterbalance is needed and it is desirable to remove any counterbalancing from the band wheel 12. In my invention this is accomplished by loosening the clamp plates 45 and sliding

the counterweight 42 along the rails 33 into concentric position, as indicated by the dotted lines 49 of Fig. 2. When in this position the counterweight has no eccentric weight upon the band wheel 12. This is a very desirable feature, since it permits the apparatus to be readily used for pumping or for pulling the rods without dismantling any parts. It is not necessary to detach the counterweight 42 from the band wheel 12. 75 75

The rails 33 are extended entirely across the band wheel 12 and serve as a binding means for securing the different parts of the band wheel rigidly together, to make a more rigid band wheel and prevent spreading of the parts. 80

From the foregoing description it is quite obvious that my invention is very valuable for the reasons already pointed out. The construction thereof is comparatively simple and it is easy to produce, making the cost of production quite low. The invention resides broadly in the rails 33 and brackets 27 and 37 which comprise the weight supporting means, the counterweight 42 and the clamp plates 45 which comprise the securing means of the invention. 90

I claim as my invention:

1. In combination: a wheel having a rim and a web portion; a shaft for rotatably supporting said wheel; reinforcing means for said wheel, said means comprising a diametrically disposed pair of parallel rails respectively positioned on opposite sides of said shaft and secured at opposite ends to the wheel rim, and intermediate brackets secured to and reinforcing said web portion and connected to said rails to prevent spreading thereof; a counter-weight mounted to slide on said rails; and means for clamping said weight to said rails in selective positions. 100

2. A combination as defined in claim 1 in which each of said intermediate brackets extends transversely to said rails and is connected to both rails to relieve said web portion of strains tending to spread the rails. 110

3. In combination: a wheel; a shaft for rotatably supporting said wheel; weight supporting means carried by said wheel and extending radially from the center thereof, said means comprising a pair of parallel rails and means for securing said rails to said wheel; a counter-weight slideable on said rails and provided with a slot so that it may be moved into a position concentric with said shaft; and means for securing said weight in selective positions on said rails. 115 120

4. In combination: a wheel; a shaft for rotatably supporting said wheel; weight supporting means carried by said wheel and extending radially from the center thereof, said means comprising a pair of parallel rails and means for securing said rails to said wheel; a counter-weight having grooves 125 130

in which said rails engage, said weight being
slidable to selective positions along said
rails; clamp plates resting in pockets formed
in said counter-weight; and means for
5 clamping said clamp plates against said rails
to retain said weight in a selected position.

5. In combination: a wheel; a shaft for
rotatably supporting said wheel; weight sup-
porting means carried by said wheel and ex-
10 tending radially from the center thereof,
said means comprising a pair of parallel
rails and means for securing said rails to
said wheel; a counter-weight having grooves
in which said rails engage, said weight being
15 slidable to selective positions along said
rails; clamp plates carried by said counter-

weight; and means for clamping said clamp
plates against said rails to retain said weight
in a selected position.

6. In combination: a wheel; a rotatable 20
shaft on which said wheel is secured; weight
supporting means extending radially across
said wheel; and a counter-weight adjustably
mounted on said weight supporting means,
said counter-weight having a slot formed 25
therein to permit it to be moved into a po-
sition concentric with said shaft.

In testimony whereof, I have hereunto set
my hand at Taft, California, this 7th day of
December, 1925.

MAX J. MILZ.
